UNITED STATES PATENT OFFICE.

DANIEL L. NEWTON, OF FULLERTON, CALIFORNIA.

EVAPORATING STILL.

Application filed August 7, 1922. Serial No. 580,269.

To all whom it may concern:

Be it known that I, DANIEL L. NEWTON, a citizen of the United States, residing at Fullerton, in the county of Orange and

5 State of California, have invented new and useful Improvements in Evaporating Stills, of which the following is a specification.

10 My invention relates to evaporating stills, particularly adapted, although not necessarily, for distilling oil to expel the gasoline from oil which has absorbed gasoline from natural gas, and for topping and other evaporating purposes.

15 It is a purpose of my invention to provide an evaporating still of the above described character in which the quick and uniform heating of the material to be treated is effected and with the utter absence of any hot spots which would decompose or 20 crack the material to be distilled.

25 Although I will describe only one form of evaporating still embodying my invention and point out the novel features thereof in claims, it is to be understood that various changes and modifications may be made without departing from the spirit of the invention and the spirit and scope of the appended claims.

30 In the accompanying drawings, Figure 1 is a view showing in vertical section one form of evaporating still embodying my invention.

35 Fig. 2 is a view showing in side elevation the evaporating still shown in Fig. 1 and connected to a conventional form of boiler.

40 Referring specifically to the drawings, in which similar reference characters refer to similar parts, my invention in its present embodiment comprises a tank 15, preferably of cylindrical form, with its lower end closed and its upper end provided with a substantially conical cover 16 which communicates at its apex with a discharge pipe 17. The tank is interiorly divided into 45 three separate and distinct compartments by means of partitions 18, 19 and 20. The chamber between the partitions 18 and 19 constitutes a steam compartment designated at 21, and the partitions are perforated at 50 corresponding points to receive pipes 22 and 23. As clearly shown in Fig. 1, the pipes 22 are arranged in three concentric series and exceed the pipes 23 in diameter for a purpose which will be hereinafter described. The pipes 23 are also arranged in 55 three concentric series and in parallel re-

lation with respect to the series of pipes 22.

The partition 20 cooperates with the bottom of the tank 15 to provide an oil receiving compartment 24 and to which oil is 60 adapted to be supplied by a pipe 25. The partition 20 cooperates with the partition 19 to form an oil collecting chamber 26, and communicating with this chamber are the lower ends of the pipes 22. The pipes 23 are extended below the lower ends of the pipes 22 and into the partition 20, so as to have communication with the compartment 24 for the purpose of conducting oil from the chamber upwardly to the upper ends of 70 the pipes 22.

The oil collected within the compartment 26 is conveyed to an exterior point by means of a pipe 27.

75 Steam is adapted to be supplied to the compartment 21 from a boiler 28 (Figure 2), this boiler being of any conventional form and having communication with the upper end of the chamber 21 by means of a pipe 29. This connection permits of the 80 circulation of steam about the several pipes 22 and 23 with a final discharge from the compartment through a pipe 30, which is preferably provided with a steam trap 31.

85 A pipe 32 conveys steam from the boiler 28 to the chamber 26, and as clearly shown in Fig. 1, this pipe is provided with discharge ports 33 disposed to discharge steam into the compartment 26 and upwardly 90 through the pipes 22.

95 As previously stated, the evaporating still is adapted for distilling oil which has absorbed gasoline from natural gas to expel the gasoline therefrom. This oil, which is commonly known as a fat oil, is supplied to the compartment 24 through the pipe 25 in such quantities as to cause it to circulate upwardly through the pipes 23 and downwardly through the pipes 22. During 100 such circulation, a rapid and uniform heating of the oil is effected by virtue of its intimate contact with the walls of the pipes and the fact that the latter are heated, as for instance to 230° F., by the high pressure steam from boiler 28. The steam ascending 105 the pipes 22 from the chamber 26 sets up a current counter to that of the falling oil thereby materially assisting in the evaporation of the latter. This heating process naturally effects an evaporation of the gasoline content of the oil with the result that 110 the gasoline vapors pass upwardly from the

pipes and ultimately out of the tank through the pipe 17 where they may be conveyed to a suitable condensing apparatus.

By the time the oil is discharged from the 5 lower ends of the pipes 22 and into the compartment 26, it is devoid of gasoline content, and this oil, which is known as lean oil, is conveyed from the compartment through the pipe 27.

10 From the foregoing description, taken in conjunction with the accompanying drawings, it will be manifest that I have provided an evaporating still of extremely simple, durable and efficient construction and 15 which operates to effect the rapid and uniform heating of any material to be treated to effect the expulsion of the desired volatile content, and with the utter absence of any hot spots which would decompose or crack 20 the material to be distilled. In its adaptation to the distillation of gasoline, it is extremely efficient as compared to similar apparatus heretofore proposed.

I claim:

- 25 1. An evaporating still comprising a vertical casing, a lower, a middle and a top partition therein forming at the bottom an oil compartment, a residual oil compartment thereabove, a steam compartment above the 30 residual oil compartment, and a vaporizing chamber at the top, a series of small bore pipes leading from the oil compartment to the vaporizing chamber, a series of large bore tubes leading from the vaporizing 35 chamber to the residual oil compartment, a steam inlet to the residual oil compartment, means for feeding oil to the oil compartment, means for withdrawing the vapors at the top of the still, means for withdrawing the residual oil, and means for introducing a heating medium into the heating compartment.
- 40 2. In an evaporating still, a tubular casing having a lower, a middle and an upper

compartment and a top chamber for the vapors, said lower compartment being adapted to be kept continuously filled with a liquid to be vaporized, a plurality of pipes communicating with said lower compartment and extending through said middle and upper compartments and adapted to be kept continuously filled to overflowing with the liquid from said lower compartment, a plurality of pipes associated with the first series of pipes into which flows the overflowing liquid from the first series of pipes, the second series of pipes extending through said upper compartment and communicating with said middle compartment, means for introducing steam into said middle compartment and into said second series of pipes, and an outlet from said casing for the liquid collected in said middle chamber.

3. In an evaporating still, a tubular casing having a lower, a middle and an upper compartment, and a top chamber for the vapors, said lower compartment being adapted to be kept continuously filled with a liquid to be vaporized, a plurality of pipes communicating with said lower compartment and extending through said middle and upper compartments and adapted to be kept continuously filled to overflowing with the liquid from said lower compartment, plurality of pipes associated with the first series of pipes into which flows the overflowing liquid from the first series of pipes, the second series of pipes extending through said upper compartment and communicating with said middle compartment, means for introducing steam into said middle compartment and into said second series of pipes, an outlet from said casing for the liquid collected in said middle chamber, and means for heating said upper compartment.

In testimony whereof I have signed my name to this specification.

DANIEL L. NEWTON.
